US00D451415B1

(12) **United States Design Patent** (10) Patent No.: **US D451,415 S**
Meyer et al. (45) Date of Patent: ** Dec. 4, 2001

(54) **LOAD CELL BODY**

(75) Inventors: **Richard A. Meyer, Carver; David M. Burru**ss, Crystal; **Michael Gary Schulz**, Eden Prairie; **Philip E. Leise**, Minneapolis, all of MN (US)

(73) Assignee: **MTS Systems Corporation**, Eden Prairie, MN (US)

(**) Term: **14 Years**

(21) Appl. No.: **29/119,642**

(22) Filed: **Mar. 3, 2000**

(51) LOC (7) Cl. **10-04**

(52) U.S. Cl. **D10/83**

(57) **CLAIM**

The ornamental design for a load cell body, as shown and described.

DESCRIPTION

FIG. 1 is a front perspective view of an embodiment of a load cell body;

FIG. 2 is a front perspective view of the load cell body of FIG. 1;

FIG. 3 is a rear elevational view of the load cell body of FIG. 1; and,

FIG. 4 is a side elevational view of the load cell body of FIG. 1;

Any broken line illustration of environmental structure in the figures is not part of the design sought to be patented.
